(57) **CLAIM**

The ornamental design for a window lock, as shown and described.

DESCRIPTION

FIG. 1 is a front perspective view of a window lock, showing my new design;

FIG. 2 is a front view thereof;

FIG. 3 is a rear view thereof;

FIG. 4 is a left side view thereof;

FIG. 5 is a right side view thereof;

FIG. 6 is its enlarged top plan view;

FIG. 7 is its enlarged bottom plan view;

FIG. 8 is a perspective view of the window lock in a state of use; and,

FIG. 9 is an enlarged detail view of area 9 in FIG. 1.

The broken lines in the drawings illustrate the portions of the window lock, which form no part of the claimed design. The dash-dot-dash broken lines encircling the enlarged views are for annotative purposes only and form no part of the claim thereof.
